[57] CLAIM

The ornamental design for an information indicator for attachment to a garment hanger, as shown and described.

DESCRIPTION

FIG. 1 is a perspective view of an information indicator for attachment to a garment hanger showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

The broken line disclosure of the numerals is for illustrative purposes only and forms no part of the claimed design.

FIG. 1

FIG. 2

FIG. 3

FIG. 4

FIG. 5

FIG. 6

FIG. 7
